REFLECTOR BUTTON

Peter Kucera, Allison Park, Pa., assignor to The
Phoenix Glass Company, Monaca, Pa., a cor-
poration of West Virginia

Application February 7, 1935, Serial No. 5,330

6 Claims. (Cl. 88—82)

My invention relates to reflectors for road signs, advertising signs, etc.

The invention comprises the use of reflector prisms or buttons which are coated on their rear surfaces with reflecting material, and are arranged in suitable patterns, on sign boards, or other supporting members.

One object of my invention is to provide a reflector button of generally simplified and improved form.

Another object of my invention is to provide an improved manner of mounting reflector buttons, so that they can be readily removed for replacement, or to permit painting of the board or other support upon which the buttons are mounted.

Some of the forms which my invention may take are shown in the accompanying drawing wherein Figure 1 is a face view of the sign; Fig. 2 is an edge view thereof; Fig. 3 is a sectional view, on an enlarged scale, of a portion of the structure of Fig. 2; Fig. 4 is a rear view of the structure of Fig. 3; Fig. 5 shows a modified form of retaining clip; Fig. 6 is a view showing a reflector button of another form, and Fig. 7 shows a further modification thereof.

In the present instance, the buttons are shown as mounted on a sign board 8, that may conveniently be of sheet metal or other suitable material. The board is perforated along desired lines to receive the buttons, which can be arranged in such formation as to conform to the lettering desired.

The buttons 9 are formed of glass or other transparent material and have enlarged rounded heads or faces. The shank portions of the buttons are of reduced diameter, and have annular grooves 10 which are spaced from the button heads a slight distance, so that when the buttons are positioned in the sign board as shown in Fig. 3, clamping rings 11 of spring wire or other suitable material can be placed in the grooves 10, and will retain the button heads in snug engagement with the sign board.

The rings 11 can be readily sprung apart to disengage them from the buttons, and to permit withdrawal of the buttons. This feature of convenient detachability is of considerable utility, in that the buttons can be readily removed to permit of painting the sign board, and also to permit of replacement with other buttons.

The buttons are provided with a reflecting coating 12 which is preferably in the form of sprayed molten metal that adheres to or becomes

fused with the glass. The metal is preferably of a light color such as aluminum.

The buttons can conveniently be coated by setting their heads into conical or hemispherical depressions in a suitable holder and coating the exposed portions thereof, including the sides and the rear end of the shank 9, as well as the rear flat surface of the head. They are coated with molten metal from a suitable spray gun.

It will, of course, be apparent that the buttons 10 will reflect light rays from headlamps or other sources of light, and be thereby given high visibility.

Referring to Fig. 5, the button and sign board arrangement may be substantially as shown in Figs. 1 to 3, but in this instance, instead of employing the split ring clips 11, I employ a clip 13 of staple-like or U form that can be pushed into position to partly embrace the buttons along their circumferential grooves 10. The legs of the clip are curved somewhat intermediate their ends so as to have adequate length of contact with the groove.

Referring to Fig. 6, I show a button 15 which is of somewhat the same general type as the other 25 buttons, but wherein no groove is required for the retaining ring or clip 16. In this case, the metal coating 17 is deposited to such thickness along a circumferential line adjacent to the head of the button as to itself form a shoulder against 30 which the retaining ring 16 may abut, to hold the button in place.

Fig. 7 shows a structure wherein the metal coating 18 is deposited to such thickness as will permit the cutting of threads thereon. These 35 threads in effect provide a shoulder portion for receiving a threaded mount element 20. In this structure, a nut 20 and a washer 21 are employed, the nut serving as a clamping member for securing the button to the sign board 22.

From the above explanation, it will thus be apparent that I have provided shoulder portions in the embodiments of my invention illustrated in Figures 3 to 6, inclusive, which receive and position an interlock or mount clip 11, 13, or 16. The 45 same principle is employed in connection with the embodiment of Figure 7 since the threads in effect provide interlock shoulder portions which receive the nut or threaded mount member 20.

Instead of applying a reflective coating to the 50 buttons, they could be made of prismatic form and of colored glass, so that they would give an appreciable degree of reflection which would be sufficient in many cases.

The buttons will be formed by casting or press- 55

ing them in suitable molds, while the glass is in a plastic state. They will be removed from the molds as soon as their surfaces have become sufficiently solidified to retain their shape. It is 5 preferable that the metal be sprayed upon the buttons while they are still hot from the mold, and while their interiors are perhaps still so hot as to be soft.

10 The buttons will therefore have a considerable quantity of stored heat which will maintain their surfaces at high temperatures, so that when the molten metal is sprayed on, there will be an adherent union effected between the metal coating and the glass. If the buttons were too cold, 15 there would not be so good fusing of the metal with the glass, and the particles of metal and glass could not adjust themselves to one another during cooling of the coated article. Ruptures and peeling of the metal are therefore not so likely to occur as if the metal were sprayed on a cold glass surface, or a glass article that did not have sufficient stored heat.

20 While I have described my invention in view of certain illustrative embodiments, it will be apparent that many changes, substitutions, additions, omissions or combinations thereof may be made without departing from the spirit and scope thereof as indicated in the appended claims.

I claim as my invention:—

- 30 1. In combination with a support, a reflector button having head and shank portions, the shank portion of said button extending through the support, a metallic reflecting coating on the shank portion of said button of sufficient thickness at certain points to form a shoulder, and a removable clip engaging the shoulder and the support for detachably holding the button in place.
- 35 2. In combination with a support, a reflector button having head and shank portions, the shank portion of said button extending through the support, a metallic coating on the shank portion of said button, said coating being light-reflecting when viewed through the head portion of said button, threads formed in a portion of

45 said coating, and mounting means detachably engaging the threads and cooperating with the support for holding the button in place on the support.

3. In combination with a support, a reflector 5 button having head and shank portions, the shank portion of said button extending through the support, a metallic reflective coating on the shank portion of said button of sufficient thickness at certain points to form a shoulder portion, and means engaging the shoulder portion and cooperating with the support for holding said button in place on the support.

4. In combination with a support, a reflector 10 button having head and shank portions, the shank portion of said button extending through the support, said reflector button being of glass, an aluminum coating on the shank portion of said button of sufficient thickness at certain points to form an interlock portion, said coating being 15 light-reflecting when viewed through the head portion of said button, and fastening means engaging said interlock portion and cooperating 20 with the support for holding said button in place on the support.

25 5. In combination with a support, a reflector button having head and shank portions, the shank portion of said button extending through the support, a metallic coating on the shank portion of said button of sufficient thickness at certain points to form a shoulder portion, and means 30 engaging the shoulder portion and cooperating with the support for holding said button in place on the support.

35 6. In combination with a support, a reflector button having head and shank portions, the shank portion of said button extending through the support, an aluminum reflective coating on the shank portion of said button of sufficient thickness at certain points to form a shoulder portion, means engaging the shoulder portion and 40 cooperating with the support for holding said button in place on the support.

PETER KUCERA.
